UNITED STATES PATENT OFFICE.

EDWIN N. CHANDLER, OF BROCKTON, MASSACHUSETTS, ASSIGNOR TO SIMPLEX ELECTRIC HEATING COMPANY, OF BOSTON, MASSACHUSETTS, A CORPORATION OF MASSACHUSETTS.

ELECTRIC HEATER FOR SHOE-OPERATIVES' KNIVES.

No. 893,783.

Specification of Letters Patent.

Patented July 21, 1908.

Application filed April 16, 1908. Serial No. 427,332.

To all whom it may concern:

Be it known that I, EDWIN N. CHANDLER, a citizen of the United States, residing at Brockton, in the county of Plymouth and 5 State of Massachusetts, have invented an improvement in Electric Heaters for Shoe-Operatives' Knives, of which the following description, in connection with the accompanying drawings, is a specification, like letters on the drawings representing like parts.

In shoe factories, knives shaped somewhat like putty knives are commonly used by the operatives in working on crippled shoes, repairing patent leather shoes, etc., and at 15 present these knives are commonly heated in the flame of a lamp, with attendant fire risk, danger of overheating the knives, etc.

The object of my invention is to provide a simple and inexpensive electric heater for 20 maintaining the knives at the desired uniform temperature.

In the accompanying drawing, in which I have shown a preferred embodiment of my invention, Figure 1 is a top plan view thereof; 25 and Fig. 2 a central vertical section.

On a suitable base 1, which may be of insulating material, wood, marble, ebonite, or any other suitable material, is mounted a stand, herein shown as having three legs, 2, to 30 whose upper end is secured a transverse plate or support 3, preferably of iron, which may or may not contain heating resistance wires, being herein shown as containing said resistance wires 4 embedded in usual porcelain or glass 35 insulation 5. Above said plate 3 is a heating plate or table 6, preferably of iron or other superior heat conductive material, secured by any suitable means, as by a screw 7 passing through a central hub 8 of the plate 3

40 into a depending hub or boss 9 of the table 6. On the under side of the latter are heating wires 10 embedded in porcelain or glass 11, in usual manner, retained and protected by depending flanges 12 which preferably fit 45 over corresponding flanges 13 of the plate 3, thereby tightly closing in the contained heating apparatus. A rheostat 14 of any usual construction, is provided on the base 1, supplied with current by wires 15, 16, and con-

50 trolled by a usual handle 17. A plug 18 is shown for convenience of circuit connection with any lamp socket or other convenient socket. Above the table 6 I secure a spring disk 19 which is hollow on its under 55 side slightly spheroidal, being held up at its

center by a washer 20 and clamped or sprung down onto the table at its periphery by a central screw 21, additional stiffness being provided by a similar but smaller disk 22.

In use, a knife blade 23 is shoved along the 60 surface of the table 6 beneath the spring disk 19, with the result that it is pinched down or held down tightly flat against the top surface of the table 6. This direct contact causes the blade to be heated very quickly. Knives 65 may be stuck under the spring holding plate 19 all around its periphery, so that the apparatus is capable of holding quite a number of knives at the same time. The holding members 19, 22 are thin and yielding, so that it 70 is not difficult to shove the sharp edge of the knife under the edge of the disk 19 simply by scraping it along the table 6.

I am aware that heating devices of various forms have been provided, and accordingly I 75 do not claim the same broadly.

My invention is a workshop convenience, designed to facilitate the heating of workmen's knives, and provide means for maintaining the knives at all times ready for instant use. The knives radiate around from the heating table in position to be readily grabbed, and the apparatus is of course of such a construction and shape that it will serve a number of workmen at the same 80 time. Its construction is such that it is exceedingly durable and cannot readily be injured. The tension of the holding springs or disks is readily varied by adjusting the screw 85 21. Preferably the lugs 2 and plate 3 are 90 cast as one piece, to constitute a stand for the apparatus, and the peripheral flanges 12 of the table rest on lugs or shouldered projections 24 projecting from the plate 3.

Having described my invention, what I 95 claim as new and desire to secure by Letters Patent of the United States is,

1. An electric knife-heater, having a flat top table, a yielding plate clamped against the top of the table to receive beneath it the 100 blade of a knife and hold the same down flat directly against the heating surface of the table, and electric heating means for maintaining said table hot.

2. A knife-heater, having a flat top table 105 of heat conductive material, a yielding holding plate centrally clamped to said table and having its peripheral edges normally in engagement with the table but capable of yielding away from the table to receive knife 110

blades and clamp them in direct contact flat against the table, and means for maintaining the table hot.

3. A knife-heater, having a flat top table 5 of heat conductive material, a yielding holding plate arch shaped in cross section, centrally clamped to said table and having its peripheral edges normally in engagement with the table but capable of yielding away 10 from the table to receive knife blades and clamp them in direct contact flat against the table, and means for maintaining the table hot.

4. A knife-heater, comprising a table of 15 heat conductive material, a clamping plate arch shaped in cross section, supporting means holding the middle of said plate away from the table, means coöperating therewith in clamping the plate with its peripheral 20 edges normally against the table to receive knife blades and hold them tight down against the heating surface of the table, and means for maintaining the table hot.

5. A knife-heater, comprising a heating 25 table, means to heat the same, a clamping

plate held at its middle away from the table and having its peripheral edges depending in normal clamping engagement with the table, a clamping spring above said clamping plate engaging the latter adjacent said peripheral edges, and means centrally clamping said spring and plate to the table.

6. A knife-heater, comprising a base, a stand projecting therefrom, a heating table 30 of heat conductive material supported on said stand, a yielding plate centrally supported above said table and having its edges normally in clamping engagement with the table to receive and clamp a knife blade against the heating surface of the table, electric heating resistance in said table, and a rheostat permanently mounted on said heater for controlling said resistance.

In testimony whereof, I have signed my name to this specification, in the presence of 4 two subscribing witnesses.

EDWIN N. CHANDLER.
